UNITED STATES PATENT OFFICE.

HERMAN J. SATTLER, SR., OF QUAKERTOWN, PENNSYLVANIA.

LET-OFF.

1,418,025.

Specification of Letters Patent. Patented May 30, 1922.

Application filed May 4, 1921. Serial No. 466,713.

To all whom it may concern:

Be it known that I, HERMAN J. SATTLER, Sr., a citizen of the United States, residing at Quakertown, in the county of Bucks and State of Pennsylvania, have invented certain new and useful Improvements in Let-Offs, of which the following is a specification.

This invention relates to improvements in let-off devices for the warp beams of looms, and more particularly to the friction type of let-off, disclosed in my Patent No. 1,019,993, dated March 13, 1912.

The invention has for its object to provide an improved structure which eliminates wear of the parts and the resultant impairment in the proper operation of the mechanism.

A further object of the invention is to provide a novel and improved means for varying the degree of the frictional engagement of the device with the warp head.

The objects stated are attained by means of a combination and arrangement of parts to be hereinafter described and claimed, and in order that the same may be better understood, reference is had to the accompanying drawing forming a part of this specification.

In the drawing,

Fig. 1 is a side elevation of the mechanism; Fig. 2 is a front elevation thereof; Fig. 3 is a sectional detail view; Fig. 4 is a view similar to Fig. 1 showing a modification; Fig. 5 is an enlarged section on the line 5-5 of Fig. 4, and Fig. 6 is a view similar to Fig. 3 showing the modification.

Referring specifically to the drawing, 5 denotes the warp head at one end of the warp beam, a fragment of the latter being shown at 6. The warp head is encircled by a band 7 of leather or other suitable flexible material which is riveted or otherwise secured to an outer metal band 8. This assembly of leather and metal bands forms a friction band, the inner or leather portion being engageable with the periphery of the warp head. The friction band is not continuous, but it is split or divided so that it may be contracted more or less to grip the warp head, and by the friction thus produced resist the rotation thereof and thereby allow the warp threads to be unwound from

the beam as fast as the cloth or other material is woven, and yet at all times keep a proper tension on the warp threads. The 55 warp head 5 is provided with radial apertures 9 opening through the periphery thereof, the purpose of which will be presently described.

To one end of the outer portion 8 of the 60 friction band is riveted or otherwise secured a shoe 10 provided with a slotted ear 11 to which is pivoted, as shown at 12, a lever 13 having at one of its ends lateral extensions 14 and 15. The extension 14 carries a pin 16 which passes through a perforation in the shoe and an aligned perforation in the friction band, so that it may seat in one of the apertures 9. The extension 15 works in the slot of the ear 11, and is adapted 65 to engage a transverse bolt 17, whereby the swing of the lever 13 is limited, and the pin 16 is prevented from being pulled out of the perforation in the shoe 10.

To the bolt 17 is connected one end of a 75 chain, or other flexible element 18, which latter, after being given several turns around the outside of the friction band, has attached to its other depending end a weight 19. The band 8 carries outstanding pins 20 between 80 which the chain is located and which prevent it from slipping sidewise off the band.

The free end of the lever 13 carries a weight 21 which tends to swing the same in a direction to insert the pin 16 into one 85 of the apertures 9. On the pin 16 are mounted washers 22 for taking up wear, one washer after the other being removed as the length of the pin is reduced by wear.

The bolt 17, alongside the ear 11, carries 90 a block 23 through which slidably passes the threaded shank 24 of a hook 25. To this hook is anchored one end of a short chain or other flexible device 26 carrying a hook 27. Back of the block 23, the shank 24 is provided with an adjusting nut 28, and a lock nut 29 for the latter.

As shown in Fig. 1, the pin 16 is extending into one of the apertures 9 in the warp head 5, whereby the friction band is locked 100 to the latter to turn or rotate therewith. It will be noted that the lever 13 is now to the right of the vertical center line of the warp head, so that it tends to hold the pin 16 in

locking position. As the warp head continues to rotate in the direction of the arrow, the friction band, rotating with the warp head, carries the lever bodily in the direction of the vertical center line of the warp head and over to the left side thereof, whereupon the lever automatically tilts and withdraws the pin 16 from the aperture 9. The friction band is now unlocked from the warp head, and it is free to turn or slide to the right, carrying the lever in the same direction, and when the lever passes to the right of the vertical center line of the warp head it tilts to the left and again inserts the pin 16 into one of the apertures 9 to lock the friction band to the warp head. The movement of the friction band to the right, when it is unlocked from the warp head, is effected by the weight 19.

20 The operation of the device is to all intents and purposes the same as the device disclosed in my Patent No. 1,019,993, hereinbefore mentioned. However the present structure is more efficient and reliable. In 25 the patented structure the rope, chain or other flexible element wound around the warp head is subject to rapid wear and weakening of its friction with the warp head, and the latter is also worn by the 30 direct contact of the shoe therewith. In the present structure, the chain or other flexible element, as well as the shoe, are not in contact with the warp head, and only the inner portion of the friction band is in contact with the warp head, and when this 35 portion of the band, which can be made of leather or woven material, becomes worn out, it can be easily renewed. The chain also produces no wear on the inner portion 40 of the friction band as it is wrapped around the outer metal band 8, and this also distributes the friction more evenly on the warp head.

45 The frictional engagement of the band 7 with the warp head 15 is produced by the chain 18, the weight 19 attached to the free end of the latter tending to draw the chain tight around the band and thereby acting to hold the same against the warp head.

50 The tension of the chain on the friction band may be varied by connecting the hook 27 to some part of the chain passing around the warp head. Assuming that the chain is wrapped around the warp head thrice, 55 then if the hook 27 is coupled to the chain at the second turn or convolution from its fixed end, it will be evident that the weight 19 is now pulling on only one turn or convolution of the chain and only this portion 60 of the chain is acting on the band to obtain the frictional engagement of the same with the warp head. If more friction is desired it is necessary only to couple the hook to the chain at a point nearer its fixed 65 end, as for instance, the first turn or con-

volution from the end. When the hook is not coupled to any part of the chain, the maximum friction is obtained, as the weight now pulls on and tightens all three convolutions of the chain around the band.

70 The hereinbefore described adjustment to vary the tension can be readily made, and it assures a perfect, smooth and easy running let-off. The mechanism not only lets off, but it also takes up to the extent of about 75 six inches without changing the tension. After the hook 27 is coupled to the chain 18, it can be drawn back, by operating the nut 28, until the chain is slack from the point of attachment of the hook to the fixed 80 end of the chain, and by means of the lock nut 29 the adjustment is securely maintained.

85 The preferred embodiment of the invention has been disclosed but it will be understood that many changes and modifications may be made without a departure from the spirit and scope of the invention as claimed hereinafter. It will also be understood that the invention may be employed in connection 90 with paper feeding rolls and other devices requiring a let-off mechanism.

95 Figs. 4 to 6 disclose a modified structure designed for use when very flimsy goods such as chiffon, taffeta, messalines, etc., are 100 to be woven. In this structure the latch pin 16 has been left off in order to eliminate the jerky motion created when the pin is suddenly pulled out of the apertures 9 as the lever 13 swings over to the left side of the vertical center line of the warp head 5.

105 The shoe 10 in the modified structure is carried by a friction band as in the first instance, but instead of the latch pin 16, there is provided an auxiliary or brake shoe 30 which is carried by the lever 13. The shoe 30 seats in a recess 31 in the inner face of the shoe 10 so that it may be pressed against the metal outer portion 8 of the friction band. The back of the shoe 30 has an outstanding web 32 which projects through a slot 33 in the shoe 10 so as to locate its rear edge opposite the pivoted end of the lever 13, 110 said slot coinciding with the space between two ears 34 on the back of the shoe 10.

115 The ears 34 have aligned transverse apertures to seat the journals 35 and 36 of a pivot pin 37 on which the lever 13 is fulcrumed. The pivot pin 37 is integral with the journal 35 and it is located off the center 120 thereof or eccentrically with respect thereto, and the journal 36 has a correspondingly located aperture to seat the outer end of the pin. Into the outer end of the pin 37 is threaded a screw 38 under the head of 125 which is a washer 39 which bears against the outer face of the journal 36 to prevent endwise separation of the pin from said journal.

130 The journals 35 and 36 are rotatable in

the ears, and they are locked in adjusted position by set screws 40 threaded through the ears 34.

The aperture in the lever 13 through 5 which the pivot pin 37 passes is located off to one side of the longitudinal center line of the lever, and this end of the lever is rounded off so as to produce a cam which is in contact with the edge of the web 32. The 10 lever 13 swings freely on the pivot pin 37, and when it is to the right of the vertical center line of the warp head 5, as shown in Fig. 4, its cam edge is pressing the shoe 30 against the friction band with sufficient 15 force to positively lock the band to the warp head for the same purpose as the latch pin 16 in the first-described structure. When the lever 13 moves over to the left of the vertical center line of the warp head, its cam 20 edge recedes from the edge of the web 32 and allows the shoe 30 to back and break the frictional engagement of the band with the warp head. The friction band is now unlocked from the warp head as before, and 25 said band is left free to slide or turn to the right, carrying the lever in the same direction to tilt and again jam the shoe 30 against the friction band, and lock the latter to the warp head.

30 The degree of the cam or eccentric action of the lever can be readily adjusted by rotating the journals 35 and 36 of the pivot pin 37.

It has also been found in practice that for 35 certain heavy goods it is necessary to combine both of the retarding elements disclosed on one double shoe.

I claim:

1. The combination with a warp head, of 40 a friction band around the same, a line wrapped around the band and having one end connected thereto, a tension device connected to the other end of the line, a lever carried by the band, and means controlled 45 by the lever for locking the band to the warp head.

2. The combination with a warp head, of 50 a frictional retarding element therefor, means for locking said element to the warp head to move therewith, means for periodically releasing the retarding element, means for returning said element to locked position when thus released, and means for varying the degree of the frictional engagement of 55 the retarding element with the warp head.

3. The combination with a warp head, of 60 a friction band around the same, a tension device engaging the band, a lever carried by the band, and means controlled by the lever for locking the band to the warp head.

4. The combination with a warp head, of 65 a friction band around the same, a tension device engaging the band, means for varying the tension of said device on the band, a lever carried by the band, and means con-

trolled by the lever for locking the band to the warp head.

5. The combination with a warp head, of 70 a frictional retarding element therefor and movable relatively thereto, means for periodically locking said element to the warp head, and means for varying the tension of the retarding element on the warp head.

6. The combination with a warp head, of 75 a friction band encircling the same, a tension device connected to the band, a pendulous element carried by the band, and means controlled by said element for periodically locking the band to the warp head to turn therewith and thereafter to release the band. 80

7. The combination with a warp head, of 85 a friction band encircling the same, a tension device connected to the band, means for varying the tension of said device, a pendulous element carried by the band, and means controlled by said element for periodically locking the band to the warp head to turn therewith and thereafter to release the band.

8. The combination with a warp head, of 90 a friction band around the same, a line wrapped around the band and having one end connected thereto, a tension device connected to the other end of the line, a pendulous element carried by the band, and means controlled by said element for periodically locking the band to the warp head to turn therewith and thereafter to release the band. 95

9. The combination with a warp head, of 100 a friction band around the same, a line wrapped around the band and having one end connected thereto, a tension device connected to the other end of the line, means for holding selected portions of the wrapped 105 portion of the line exempt from the influence of the tension device, a pendulous element carried by the band, and means controlled by said element for periodically locking the band to the warp head to turn therewith and thereafter to release the band.

10. The combination with a warp head, of 110 a friction band around the same, a line wrapped around the band and having one end connected thereto, a tension device connected to the other end of the line, a holding device anchored to the band and engageable with selected portions of the wrapped portion of the line for holding the same exempt from the influence of the tension device, means for operating said holding device for producing a slack in such 115 exempted portion of the line, a pendulous element carried by the band, and means controlled by said element for periodically locking the band to the warp head to turn therewith and thereafter to release the band. 120

11. The combination with a warp head, of 125 a friction band around the same, a line wrapped around the band and having one end connected thereto, a tension device connected to the other end of the line, a hold-

- ing device anchored to the band and engageable with selected portions of the wrapped portion of the line for holding the same exempt from the influence of the tension device, a pendulous element carried by the band, and means controlled by said element for periodically locking the band to the warp head to turn therewith and thereafter to release the band.
- 5 12. The combination with a warp head, of a friction band around the same, a shoe engageable with the band for locking the same to the warp head, a support for the shoe carried by the band, a pendulous element carried by the support and having means for periodically operating the shoe to lock
- the band to the warp head and thereafter to release the same, and a tension device connected to the band.
- 10 13. The combination with a warp head, of a friction band around the same, a shoe engageable with the band for locking the same to the warp head, a support for the shoe carried by the band, a pendulous element carried by the support and having a cam portion periodically operating the shoe to lock the band to the warp head and thereafter to release the same, and a tension device connected to the band.
- 15 In testimony whereof I affix my signature. 30

HERMAN J. SATTLER, SR.
